UNITED STATES PATENT OFFICE.

ARGUS O. ZINN, OF LOS ANGELES, CALIFORNIA.

DEEP-WELL PUMP.

Application filed January 10, 1924. Serial No. 685,308.

To all whom it may concern:

Be it known that I, ARGUS O. ZINN, a citizen of the United States, and resident of Los Angeles, county of Los Angeles, State of California, have invented new and useful Improvements in a Deep-Well Pump, of which the following is a specification.

This invention relates to a pump adapted for use in wells wherein there is an appreciable stretch in the piston rod on its operating stroke. Pumps of this character do not lift a volume of liquid commensurate with their capacity, because of the failure of the piston to travel a distance equal to the travel of the piston rod at the surface or at the operating head. There is also slapping of the rod, and crystallization due to the alternate expansion and contraction of the rod. This weakens the rod and may cause breaking.

The objects of this invention are first, to provide a pump having means to produce and maintain an initial stretch in the pump rod; second, to provide and maintain a confined column of liquid thereby providing in effect a rigid piston rod; third, to provide a valved piston of the characteristics before specified and having a tubular rod for the discharge of the pumped liquid therethrough; and fourth, to provide a pump of the characteristics before specified and having a uniflow of liquid.

These objects together with other objects and corresponding accomplishments are obtained by means of the embodiment of my invention illustrated in the accompanying drawing, in which:

Fig. 1^A shows the upper or operating end of a pump, the view being in axial section; and Fig. 1^B shows in axial section the bottom of the pump.

Referring more particularly to the drawing, the usual conductor casing extending into the hole is indicated by 2. Disposed therein and extending therethrough is a string of casing 3, which is the usual water string, sealed at the bottom by a bond of cement 4. Disposed within the water string and extending therethrough is an oil string 5 extending into the oil strata and perforated to admit oil thereto. Disposed within the upper portion of the oil string is a jacket casing 6, which has disposed therein pump tubing 7. The water string has a casing clamp 8 mounted upon the top thereof to support the oil string, and mounted upon the

oil string is a casing clamp 9, upon which rests the collar 10 of the pump jacket. The usual pump barrel 11 is secured to the bottom of the pump tubing. A valve seat at the bottom of the pump tubing has mounted thereon a standing valve 12 of a well known type. The standing valve is provided with the usual garbut rod 13. The space between the pump tubing 7 and the jacket 6 is closed at the top and bottom. Ports 14 serve for communication between the jacket space and the interior of the pump tubing.

An upper piston 15 is slidably mounted within the pump tubing. This piston is provided with a central bore 16 enlarged in diameter at the lower end and threaded to receive the pump rod tubing 17. An abutment collar 18 is mounted upon the upper piston above the pump tubing, and above the collar is a nipple 19. A T fitting 20 connects nipple 19 with flexible pipe 21 serving to convey the oil discharged by the pump. Secured to the upper piston is a pump operating head, a portion of which is indicated generally by 22. This head serves to reciprocate the piston. Secured to the lower end of the pump rod tubing is a valved working piston 23, slidably mounted in the pump tubing. Connected to the pump jacket and communicating therewith is pipe 24 shown with a pressure gauge 25 connected thereto. A valve 26 controls communication between piping 24 and a flexible pipe 27 leading to a means for maintaining the liquid under pressure.

An incompressible liquid is forced into the jacket 6 through pipe 24 so that it fills the space in the jacket and the annular space between the pump rod tubing 17 and the pump tubing 7. Pressure is exerted upon the lower face of piston 15 and the upper face of lower working piston 23. This pressure is made sufficient to stretch and elongate the pump rod tubing, thereby making the latter rigid. The liquid maintained under pressure in the space between the pump rod tubing and the pump tubing will take the strain exerted on the downward stroke.

On the downward stroke liquid below the lower piston is forced upwardly through the valve port therein, the standing valve closing. On the upper stroke, the column of liquid within the pump rod tubing is lifted, the displacement of the lower piston drawing oil into the lower portion of the pump tubing.

What I claim is:

1. A pump having a pump barrel, a working piston disposed in said barrel, a relatively long piston rod secured thereto, an upper piston secured to said rod adjacent the top thereof, pump tubing in which said upper piston operates extending to said working barrel to form a closed chamber, and a liquid confined in said chamber under pressure.
2. A pump having a pump barrel, a reciprocable piston therein, a relatively long tubular piston rod for the discharge of liquid being pumped, pump tubing extending upwardly from said barrel and surrounding said rod to form a closed chamber, and a liquid in said chamber under pressure and hydrostatically acting upon said rod so as to provide and maintain a tension in said piston rod.
3. A pump having a pump barrel, a reciprocable piston therein, a relatively long tubular piston rod for the discharge of liquid being pumped, pump tubing extending upwardly from said barrel and surrounding said rod to form a closed chamber, a liquid confined in said chamber under pressure so as to stretch said piston rod, and means to introduce to and maintain said liquid under pressure in said chamber.
4. A pump having a pump barrel, a reciprocable working piston therein, a relatively long tubular piston rod for the discharge of

liquid being pumped, an upper piston mounted on said rod, pump tubing extending upwardly from said working barrel and surrounding said rod and upper piston to form a closed chamber.

5. A pump having a pump barrel, a valved reciprocable working piston therein, a relatively long tubular piston rod for the discharge of liquid being pumped, an upper piston mounted on said rod, pump tubing extending upwardly from said working barrel and surrounding said rod and upper piston to form a closed chamber, a liquid confined in said chamber under pressure so as to stretch said piston rod, and means to introduce to and maintain said liquid under pressure in said chamber.

6. A pump having a pump barrel, a valved reciprocable piston therein, a relatively long tubular piston rod for the discharge of liquid being pumped, pump tubing extending upwardly from said barrel and surrounding said rod to form a closed chamber, a liquid confined in said chamber under pressure so as to stretch said piston rod, and a jacket surrounding said tubing and communicating therewith whereby to introduce to and maintain said liquid under pressure in said chamber.

In witness that I claim the foregoing I have hereunto subscribed my name this 3rd day of January, 1924.

ARGUS O. ZINN.
